UNITED STATES PATENT OFFICE

ADOLPH E. ECKERT, OF CLEVELAND, OHIO, ASSIGNOR TO THE RUSS MANUFACTURING COMPANY, OF CLEVELAND, OHIO, A CORPORATION OF OHIO

REFRIGERATED CABINET

Application filed September 14, 1928. Serial No. 305,884.

This invention relates to refrigerator cabinets and particularly to cabinets for soda fountain use and the like.

One of the objects of the invention is to provide a cabinet of the above designated character in which more uniform storage temperatures are maintained in the material stored therein than in previously proposed cabinets.

10. An additional object of the invention is to increase the storage capacity of cabinets of the above designated character.

An additional object of the invention is to provide an improved form of brine tank for cabinets of the above designated character in which the brine is of substantially the same temperature gradient from the bottom to the top of the brine tank, thereby avoiding the gradually increasing temperature gradient near the upper surface of the brine tank, as in previously proposed constructions.

An additional object of the invention is to provide a brine tank in which the brine substantially fills the tank.

An additional object of the invention is to provide means for thermosyphon circulation of brine in the syrup pump rack.

30. A further object of the invention is to provide an improved form of brine tank for use in cabinets of the above designated character.

Figure 1 of the accompanying drawings is a top plan view with parts broken away to show the brine connection to the syrup rack;

Fig. 2 is a front elevation of the cabinet shown in Fig. 1;

Fig. 3 is an end elevation of the cabinet shown in Fig. 2;

Fig. 4 is a transverse sectional view of the cabinet shown in Fig. 2, taken substantially on lines 4—4 thereof;

Fig. 5 is a transverse sectional view of the cabinet shown in Fig. 2, taken substantially on line 5—5 thereof;

Fig. 6 is a corresponding transverse sectional view of the cabinet shown in Fig. 2, taken on line 6—6 thereof;

50. Fig. 7 is a top plan view of a modified

form of refrigerator cabinet built in accordance with my invention;

Fig. 8 is a front elevational view of the cabinet shown in Fig. 7 with the brine tank shown partially in section on the line 8—8 in Fig. 7;

Fig. 9 is a transverse sectional view of the cabinet shown in Fig. 8, taken substantially on the line 9—9 of Fig. 8; and

Fig. 10 is a transverse sectional view of a portion of the syrup rack of a cabinet built in accordance with the invention and showing a modified form of cooling unit for refrigerating the syrup rack.

The refrigerating cabinet that has been selected for the purpose of illustrating and describing the general principles of the invention is lined on all sides by heat insulating material 1 such as layers of cork or other material that serve to minimize the absorption of heat by the enclosed brine tanks 2 and 3. The brine tanks are mounted in separately insulated compartments 4 and 5 or are otherwise suitably insulated, one from the other, in order that the refrigerating temperatures of the compartment controlled by brine tank 3 will be of a different temperature from the compartment controlled by brine tank 2. A storage compartment 6 is arranged at one end of the cabinet and a water-cooling unit 7 is arranged adjacent the storage compartment. The compartment 6 is intended for the storage of bottled goods and the like and the water cooling unit 7 is intended for the cooling of drinking or carbonated water or like use.

The brine tank 2 is provided with a suitable evaporator 8 and is filled with brine or other suitable circulating liquid. The term "brine tank" is used herein in its broadest sense, including tanks containing any suitable liquid of low freezing point. The refrigerating unit may be of any conventional form having suitable expansion coils 9 that are submerged in the brine of tank 2 and connected with a suitable compression unit (not shown) by outlet and inlet pipes, respectively marked 10 and 11.

A suitable food-receiving chamber 12 for use as a low temperature storage compart-

ment for brick ice-cream and the like extends downwardly into tank 2 and is surrounded on four lateral sides by the brine tank 2. The chamber 12 also has an open 5 storage space 13 underlying the brine tank and suitable for the storage of brick ice-cream and the like. The chamber 12 is thereby maintained at the lower temperature of the cabinet compartments. A heat insulating cover 12a of conventional design provides access to the storage chamber 12.

The refrigerator unit 8, or evaporator as it is conventionally termed, is automatically controlled to maintain the brine temperature in the tank 2 between suitable low temperature limits, suitable for the storage of such material in the compartment 12 as is desired.

The second or supplemental tank 3 is connected to the main brine tank 2 by means of a suitable communicating pipe 14 that connects an intermediate portion of the tank 3 with a suitable opening formed in tank 2 and a return brine circulating pipe 15 that 25 is provided with a suitable control valve 16 for regulating the thermosyphon circulation of brine between tanks 2 and 3.

The communicating pipe 14 is offset from the brine tanks 2 and 3, either laterally or 30 below the associated brine tanks, in order that it will not interfere with the free use of the food-receiving openings extending through the respective brine tanks and opening into the underlying chambers, 13 of the 35 main compartment 4, and 17 of the supplemental compartment 5.

From the upper end of the brine tank 2 to the remote end of the brine tank 3, a suitable conduit 18 for the thermosyphon circulation of brine through the syrup pump rack 19 is provided. This brine-conducting conduit 18 may assist in the cooling of the storage compartment 6 if desired. A suitable valve 20 controls the rate of brine circulation from the connection of the pipe 18 to the supplemental tank 3 back to the upper part of the main tank 2. This provides considerable difference in elevation, with a sufficient temperature drop to insure proper circulation of brine through the pipe for 45 cooling the syrup rack. The syrup rack 19 is of conventional design, having suitable pumps, such as 21, that are used to dispense 50 any desired syrups and other syrup containers 22 that may or may not be supplied with 55 corresponding pumps.

Sweet and carbonated water is supplied to the draught arms 23 and 24 through suitable 60 pipe connections 25 and 26 that extend through a supplemental brine tank 27 that is cooled from an evaporator 28 to the desired temperature. The evaporator 28 may be operated from a suitable control 65 valve connected to the main line that sup-

plies the evaporator 8 with liquid refrigerant or by independent means as desired.

Operation of the above described cabinet is substantially as follows: The evaporator 8 is controlled to maintain the brine contained within the tank 2 within suitable predetermined temperature limits. Since the main body of the evaporator 8 is positioned above the opening into the food-receiving chamber 12 which is within the brine tank 2 and refrigerated thereby, the entire compartment refrigerated from the brine tank 2 will be cooled to substantially the same degree. In former constructions, the liquid level in the evaporator was below the top of the brine contained within this main tank and as a result, the upper stratum of brine in tank 2 was materially warmer than the brine below the level of the refrigerant. Because of this warmer surface brine, the upper portion of the cabinet could not be effectively used for the storage of brick ice cream and the like, because of the warm layer of brine surrounding this portion of the cabinet. By elevating the evaporator to a point where the level of the liquid refrigerant within the evaporator is above the opening into the storage compartment cooled from tank 2, the entire storage compartment is cooled to the same degree, thus rendering the entire compartment available for use for the storage of the same material, such as brick ice cream. Furthermore, the elevation of tank 2 to substantially the level of the soda rack provides means for obtaining thermosyphon circulation of brine through the soda rack. It is obvious that this could not be accomplished with the prior form of brine tank.

The thermosyphon circulation of brine between the main tank 2 and the supplemental tank 3 is controlled substantially in accordance with the principles outlined in James T. Smith's Patent No. 1,675,280. This provides a storage cabinet controlled from the supplemental tank that has all of the cooling advantages, as regards uniform temperature and the like, that is provided in the patented construction, together with the greater depth of the main brine tank 2 that facilitates the circulation of brine between the main tank and supplemental tank 3 whereby the temperature of the compartments controlled from the brine tank 3 is materially more uniform than could otherwise be obtained.

The modified form of soda cabinet shown in Figs. 7, 8 and 9 employs a main tank 30 which has an evaporator unit of materially greater capacity than that shown in the cabinet illustrated in Figs. 1 to 6, inclusive. The tank 30 extends the full width and depth of the cabinet and is provided with a supplemental offset portion 31 that has a food-receiving compartment 32 extending

therethrough which has an enlarged lower portion 33. A suitable opening that is closed by cover 34 of conventional design provides access to the food-receiving compartment 32 lying within and beneath the offset portion 31 of the tank. The location of the opening into the food-receiving compartment well below the level of the refrigerant in the brine tank insures brine of uniformly cold temperature for the entire height of the food-receiving compartment.

A supplemental tank 35 similar to the tank 3 in the modification first described is connected to the offset portion 31 of the main tank 30 by means of a suitable circulation conduit 36, similar to the conduit 14 in the previously described unit. A return circulation conduit 37 which has a suitable control valve 38 connects the upper portion 20 of the tank 35 with the elevated portion of the tank 30 in order to insure satisfactory thermosyphon circulation between tanks 35 and 30.

In this refrigerating cabinet, a conduit 39 is provided for circulating brine from the tank 35 through the syrup rack back to an elevated portion of the tank 30 and this conduit extends through a suitable water bath 40 as shown in Fig. 11 which is supplied 40 with sweet water which may be frozen around the brine return pipe 39 to provide any desired degree of ice formation, the formation of the ice coating retarding the thermosyphon circulation through the pump rack 35 and establishing a balance to maintain the temperature of the syrup cans substantially uniform. It is unnecessary, however, to cool the water bath 40 sufficiently to obtain an ice formation because the cooling of the water bath to the desired temperature above freezing will suitably refrigerate the syrup cans and the thermal capacity of the water contained in the water bath 38 satisfactorily accomplishes the cooling of the rack.

The operation of the cabinets shown in Figs. 7 to 10 inclusive is substantially the same as the operation of the cabinets shown in Figs. 1 to 6 inclusive, the difference being that the cabinets shown in Figs. 7 to 10 inclusive must be somewhat longer than the cabinets shown in Figs. 1 to 6 inclusive because of the arrangement of the main tank. The modified form of refrigerating the syrup rack shown in Figs. 7 to 10 may also be used with the cabinets shown in Figs. 1 to 6.

Although I have illustrated and described only two modifications of my invention, it will be apparent to those skilled in the art 60 that other modifications may be made without departing from the invention.

What I claim is:

1. A refrigerated cabinet comprising a main brine tank, a supplemental brine tank 65 in heat interchanging relation therewith,

and a syrup rack and means for establishing thermosyphon circulation between said tanks including a thermosyphon circulation conduit from the supplemental tank through a portion of the syrup refrigeration rack and back to the main tank for refrigerating the syrup rack. 70

2. A cabinet of the character described having a main brine tank and a supplemental brine tank alongside the main tank and of less height than the main tank, said main tank having a portion of substantially the same height as the supplemental tank, food storage compartments within said tanks opening to the top thereof, an evaporator in the main tank having the level of liquid refrigerant therein above the storage compartments, and means for establishing a thermosyphon circulation between said tanks. 75

3. A cabinet of the character described having a main brine tank and a supplemental brine tank alongside the main tank and of less height than the main tank, food storage compartments within said supplemental tank opening to the top thereof, an evaporator in the main tank having the level of liquid refrigerant therein above the storage compartments, and thermosyphon circulation conduits connecting said tanks, one of said conduits being connected to the main tank above the level of said compartments. 80

4. A soda cabinet comprising a brine tank having portions of different heights, a food storage compartment opening to the top of the portion of the tank of lesser height, and an evaporator in the portion of the tank of greater height having the level of liquid refrigerant therein well above the top of the storage compartment. 100

5. A soda cabinet comprising a main brine tank, a supplemental brine tank of less height than the main tank and positioned alongside the same, a food storage compartment in the supplemental tank which opens at the top of the supplemental tank, an evaporator located in the main brine tank and having the level of liquid refrigerant therein maintained well above the top of the supplemental brine tank, and thermosyphon circulation conduits connecting to the main and supplemental brine tanks. 115

6. A refrigerating cabinet comprising a main brine tank, a supplemental brine tank alongside the main tank and of less height than the main tank, a syrup rack mounted upon the top of the supplemental brine tank along the front thereof, a row of food storage compartments in the supplemental tank opening to the top thereof rearwardly of the syrup rack, an evaporator in the main tank having the level of liquid refrigerant therein above the tops of said food storage compartments, and means for establishing a 120

125

130

thermosyphonic circulation between said tanks including a conduit extending through a portion of the syrup rack.

7. A refrigerating cabinet comprising a main brine tank having portions of different heights, a supplemental brine tank alongside the main tank and of substantially the same height as the lower portion of the main tank, a syrup rack mounted upon the top of the supplemental tank and extending along the front thereof, food storage compartments in the supplemental tank opening to the top thereof rearwardly of the syrup rack, a food storage compartment in the main tank opening to the top of the lower portion thereof, an evaporator in the main tank having the level of liquid refrigerant therein above the tops of said food storage compartments, and thermosyphon circulation conduits connecting said tanks.

8. A refrigerating cabinet comprising a main brine tank having portions of different heights, a supplemental brine tank alongside the main tank and of substantially the same height as the lower portion of the main tank, a syrup rack mounted upon the top of the supplemental tank and extending along the front thereof, food storage compartments in the supplemental tank opening to the top thereof rearwardly of the syrup rack, a food storage compartment in the main tank opening to the top of the lower portion thereof, an evaporator in the main tank having the level of liquid refrigerant therein above the tops of said food storage compartments, and thermosyphon circulation conduits connecting said tanks, one extending through a portion of the syrup rack.

40 In testimony whereof I affix my signature.
ADOLPH E. ECKERT.
